(57) CLAIM

We claim the ornamental design for an utensil, as shown and described.

DESCRIPTION

FIG. 1 is a perspective view of an utensil, showing our new design;

FIG. 2 is a top plan view thereof;

FIG. 3 is a bottom plan view thereof;

FIG. 4 is a front elevational view thereof;

FIG. 5 is a rear elevational view thereof; and,

FIG. 6 is a left-side elevational view thereof, the right-side elevational view being a mirror image thereof.
